(57) **CLAIM**

The ornamental design for a chemical receptacle for a chemical diffusing apparatus, as shown and described.

DESCRIPTION

FIG. 1 is a top plan view of the chemical receptacle for a chemical diffusing apparatus of the present invention, the bottom view being a mirror image thereof;

FIG. 2 is a front view thereof;

FIG. 3 is a right side view thereof, the left side view being a mirror image thereof;

FIG. 4 is a back view thereof;

FIG. 5 is an enlarged cross-sectional view taken along lines V—V of FIG. 2;

FIG. 6 is a perspective view thereof; and,

FIG. 7 is an exploded view showing a chemical impregnated disk for use in the chemical receptacle of the present invention.

The broken line showing an impregnated disk usable in the chemical receptacle in FIG. 7 is for illustrative purposes only and forms no part of the claimed design.
